(57) CLAIM

The ornamental design for shorts, as shown and described.

DESCRIPTION

FIG. 1 is a front perspective view of shorts showing our new design;

FIG. 2 is a rear perspective view thereof;

FIG. 3 is a front view thereof;

FIG. 4 is a rear view thereof;

FIG. 5 is a side view thereof; and,

FIG. 6 is a second side view thereof.

The broken lines immediately adjacent to the shaded area define the bounds of the claimed design and form no part thereof. The broken lines showing the remainder of the shorts represent unclaimed subject matter and form no part of the claimed design.

1 Claim, 6 Drawing Sheets
